UNITED STATES PATENT OFFICE.

MARIANNE HOFFMANN, OF BROOKLYN, NEW YORK.

DRESS SHIELD.

Application filed January 11, 1929. Serial No. 331,870.

The object of my invention is to provide a dress-shield or protector capable of being readily attached to or detached from a garment.

5 Another object is to provide a dress shield having a fastening means concealed therein and in a position where it cannot, when in use, come in contact with the flesh of the wearer.

10 Another object is to provide a dress-shield having a concealed metal fastening secured in position so as to be readily attached and detached from the shield.

15 Another object is to provide certain improvements in the form, construction and arrangements of the parts whereby the above named and other objects may be effectively attained.

I am well aware of the fact that quite a 20 number of inventions in this particular field have been made and patents secured, but as far as I could ascertain not a single one of these improved dress shields has permanently 25 found its way into the trade. Either they proved to be too complicated, and therefore too expensive or too cumbersome for the wearer, or last but not least, were so difficult to place into or out of position that women resorted to fixing the shields by safety pins if 30 they took not the pains to sew them on. My invention avoids all these disadvantages, is very simple in construction and therefore inexpensive to manufacture.

A practical embodiment of my invention 35 is represented in the accompanying drawing in which

Fig. 1 represents a side elevation of my improved dress-shield showing the means of fastening the same to the garment,

40 Fig. 2 represents a detail vertical section on an enlarged scale taken in the plane of the line II—II of Fig. 1,

45 Fig. 3 represents a detail plan view on the same scale as Fig. 1 of a portion of the inner and outer members of the dress-shield showing the manner of securing the fastening means to the inner member of the shield,

50 Fig. 4 represents a detail side elevation partly broken away of a modified form of dress-shield and the manner of securing the fastening means to the same.

The dress-shield shown in Figs. 1 to 3 inclusive comprises two members 1 and 2. The two members are sewed together along the 55 peripheral edges as indicated by the dotted line 3. The bights 4—5 of the inner and outer members 1—2 respectively are only connected at the ends by the stitches 3. Adjacent the bight 4 of the inner member 2 60 there is provided a series of elongated slots 6, arranged in pairs, as shown in Fig. 3. In order to secure the dress-shield to the arm scye 7 of the garment 8, I provide fastening means preferably in the form of metal 65 clamps, each of which comprises arms 9—10 connected at 11. The clamps are attached to the inner members by inserting the arms 9—10 through a pair of slots 6 so the arms 9—10 will project therethrough in position 70 to be pinched on the arm scye 7 of the garment 8. The arms 9—10 may be provided with teeth 12 which penetrate the garment and enter apertures 13 in the opposite arm and in register therewith. 75

In the modified form shown in Fig. 4 the dress-shield 14 consists of a single member only having flexible loops 15 of thread or other suitable material secured thereto, upon each of which loops 15 a clamp is arranged 80 to straddle and engage the arm scye of the garment. From the foregoing it will be seen that the dress-shield will be securely fastened to the garment, and easily and readily removed if desired. Furthermore, one advantageous feature of my invention is the fact that the metal clamp is protected and cannot come in contact with or touch the flesh of the wearer when in use. 85

It is obvious that various changes may 90 be resorted to in the form, construction and arrangement of the several parts without departing from the spirit and scope of my invention; and hence, I do not intend to be limited to the details herein shown and described except as they may be included in the claims. 95

What I claim is:

1. A dress-shield provided with at least one bifurcated fastening device adapted to 100 engage the garment, and means on opposite sides of the bight of the shield for receiving said device in straddled relation for removably holding and concealing the device.

2. A dress-shield provided with a series of holes adjacent the bight and at least one bifurcated fastening device having its free ends arranged to project through said holes 5 in position to engage the garment.

3. A dress-shield provided with an inner and an outer member, said inner member

having a series of holes adjacent the bight, and at least one bifurcated fastening device 10 having its free ends arranged to project through said holes in position to engage the garment.

MARIANNE HOFFMANN.
